Patented Sept. 24, 1918.

By William W. Deane
his Attorney

UNITED STATES PATENT OFFICE.

PAUL W. AMLIE, OF BINFORD, NORTH DAKOTA.

GAME APPARATUS.

1,279,634.

Specification of Letters Patent. Patented Sept. 24, 1918.

Application filed October 4, 1916. Serial No. 123,677.

To all whom it may concern:

Be it known that I, PAUL W. AMLIE, citizen of the United States, residing at Binford, in the county of Griggs and State of 5 North Dakota, have invented certain new and useful Improvements in Game Apparatus, of which the following is a specification.

My present invention pertains to game 10 apparatus and consists in improved means for actuating and controlling the finger bar or deflector forming part of the apparatus disclosed in my Letters Patent 858,776 of July 2, 1907, as hereinafter described and 15 definitely claimed.

In the accompanying drawings:—

Figure 1 is a longitudinal sectional view of my improved game apparatus.

Fig. 2 is a transverse sectional view there- 20 through, and

Fig. 3 is a detail perspective view of the actuating means for the finger bar.

Like numerals designate corresponding parts in all of the figures of the drawing.

Referring to the drawing 5 designates a table-like member inclined both longitudinally and transversely and inclosed by a rear wall 6, a front wall 7 and end walls 8. The structure is suitably supported upon 30 legs 9 and preferably though not necessarily has disposed therebeneath book-shelves 10 and 11 by virtue of which the device is caused to serve the double purpose of a game apparatus and a book-case. Extending 35 transversely and part way across the table 5 are bars 12 spaced to form stalls 13. The open ends of these stalls are disposed adjacent a trough 14. Upon the opposite side of the trough, a finger bar 15 is slidably 40 mounted to move toward and from the stalls and this bar carries a plurality of fingers 16. A board 17 overlies the finger bar 15 and a transparent plate 18 overlies the stalls 13 and serves not only to render the interior 45 of the stalls visible but provides means for receiving numerals 19 which give to the stalls their several values. The parts so described, with the exception of the book-shelves, correspond to the showing in the 50 aforesaid patent. The present invention particularly relates to improved means for actuating the finger bar 15. This improved means comprises a pair of substantially L shaped members, (see Fig. 3) which com-

55 comprise a horizontal body portion 21 disposed under the table 5, vertical members 22 which

extend through the table, horizontal portions 23 which project forwardly over the finger bar and down-turned ends 24 which engage in the finger bar. These L shaped members 60 are connected by a longitudinally extending bar 25 by means of which they are caused to move in unison. Springs 26 extend between the rear wall 6 and the L shaped members and serve to normally hold the finger bar in 65 retracted position. A rod 27 is pivoted at 28 to a horseshoe shaped handle 29. This handle is provided with trunnions 30 by means of which it is pivoted to the front wall 7. The rear end of the rod 27 is connected with the bar 25. Any desired form 70 of connection may be used but I prefer to pass the end of the rod 27 through a keeper 28^a that is carried by the bar 25 and to adjustably fix the rod in this keeper by means 75 of a set screw 30^a, by means of which the throw of the finger bar may be adjusted. It is apparent that by pressing outwardly and downwardly upon the handle, rod 27 will be moved forwardly together with the connected parts and against the tension of the springs. When the handle is released, the 80 springs will act to return the parts to their normal position.

By virtue of the peculiar horseshoe shape 85 of the handle, the likelihood that the handle will catch in the clothing of persons passing thereby is avoided and by reason of the short throw permitted the handle, reckless and noisy operation of the device is prevented. 90

The operation of the game apparatus is the same as the operation of the apparatus in the aforesaid patent; that is, a ball is rolled along the trough 14 and the operator 95 endeavors by moving the finger bar forward through the connections described to trap the ball in a stall having a high value.

The nicety with which the finger bar 15 can be adjusted through the medium of the handle 29 and its connections opposed by the 100 retractile springs 26, constitutes the most important feature of the present invention, it being understood in this connection that in manipulating the apparatus the player watches the ball during the passage of the 105 same along the trough 14 and at the proper time moves the handle 29 outwardly and downwardly, thus to move the finger bar toward the right in Fig. 2 and thereby enable one of the fingers 16 on said bar to engage 110 the ball and deflect it into one of the stalls 13. The aim of the player is to place the ball in

the stall bearing the largest number, and while this is difficult the sensitiveness of my improved means for moving the finger bar 15 enables the player after practice to dis-
5 play considerable skill and in that way contributes materially to the amusement ca-
pacity of the apparatus. The improved means for actuating the finger bar 15 is also advantageous because it is not liable to
10 be damaged by careless players and its handle 29 is not likely to catch in the cloth-
ing of persons moving adjacent to the ap-
paratus.

While the elements shown and described
15 are well adapted to serve the purpose for
which they are intended, it is to be under-
stood that the invention is not limited to
the precise construction set forth but that it
20 includes within its purview such changes as
fairly come within the spirit of the appended
claim.

Having described my invention what I
claim is:—

The herein described game apparatus
25 comprising an inclined table provided with

a plurality of stalls open at their inner ends,
a finger bar movable laterally above the ta-
ble and toward and from the open ends of
the stalls, L-shaped members fixed to the
finger bar and reaching downwardly there-
from and then toward one side of the table,
a longitudinal bar connecting the ends of
the L-shaped members remote from the fin-
ger bar, retractile springs connecting the L-
shaped members with the table and tending
30 to move and hold the finger bar away from
the open inner ends of the stalls, a handle
located at said side of the table and pivoted
at its lower end thereto in position to swing
outwardly and inwardly, and a rod inter-
posed between and connecting the longitudi-
nal bar and the handle, said rod being at-
tached to the handle at an intermediate
35 point in the height thereof.

In testimony whereof I affix my signature 45
in presence of two witnesses.

PAUL W. AMLIE.
